2 Claims. (Cl. 318—6)

This invention relates to the art of electric drives and has particular relationship to a drive for a web such as pulp or semi-finished paper being processed in a paper mill. Typically this invention concerns itself with a drive for advancing a web through a calender dryer having a plurality of rolls. The web is advanced from an output or first calendar to the calender dryer and from the calender dryer to an input or second calender. The calender dryer, the input calender and the output calender are separately driven and the drives are adjustable so that the web may be tensioned either between the input calender and the dryer or between the dryer and the output calender. Usually the drives of the first and second calenders deliver substantially greater power than the drive of the calender dryer. Typically, the first and second calenders may have drives capable of delivering 400 horsepower while the calender dryer may have a 40 horsepower drive. Where tension is applied to the web as it is moving between the calender dryer and the second calender the second calender may be driven at a higher speed than the first calender. Under such circumstances, the motor of the calender dryer drive operates regeneratively. Where the tension is to be applied to the part of the web between the first calender and the dryer the motor is supplied with power and the drive may be described as operating generatively.

Because of the driving interconnection between the first and second calenders and the calender dryer and because the calender dryer drive is of relatively low power, it is desirable that the calender dryer drive be prevented from being excessively loaded during normal operation. This object is achieved by setting the speed control of the calender dryer so that the power supplied to the drive is below that at which full speed would be produced. In addition, current limiting facilities are provided which limit the loading of the drive during normal operation generally to the rating of the calender dryer drive. Typically, the current limit facilities may permit adjustment of the loading of the calender dryer drive to between 30% and 110% of rated loading.

In apparatus in accordance with the teachings of the prior art, the current limit is set generally to limit the loading of the calender dryer drive motor to rated loading throughout the whole operation of the apparatus, both during normal running process and during the threading process. The apparatus is threaded both at the start of an operation and also on the occurrence of a break in the web. During the threading, the speed of the calender dryer motor is adjusted in accordance with the teachings of the art by a resistor which is usually referred to as the "Draw Adjust" rheostat. Typically, on the average about three breaks per day occur and following each break it is necessary in accordance with the teachings of the prior art to rethread the web using the Draw Adjust rheostat to bring the calender dryer motor up to speed.

In the use of the prior art apparatus, it was found that the calender dryer motor consumes a relatively long time in coming up to speed. Typically, the interval so consumed is of the order of about four minutes. Apparatus of the type described here treats web at the rate of about 1000 feet per minute; delay of 4 minutes per break or 12 minutes per day results in a loss of

2

12,000 feet of the paper product per day. In a typical situation the width of the paper may be 100 inches or roughly 8 feet. Twelve minutes shut-down time would then result in a loss of 96,000 feet. The paper produced may weigh about 36 pounds per 3000 square feet. The loss from shut-down time would then amount to about 1200 pounds. At 50 cents per pound this loss amounts to \$600 per day or \$180,000 for a 300 day year.

It is then an object of this invention to reduce the loss arising from the shut-down time following a break in the web during processing.

A more specific object of this invention is to reduce the time taken for web treating apparatus as disclosed herein to reach normal operating speed following shut-down occasioned by a break in the web.

A more specific object of this invention is to provide a novel drive for a calender dryer, the use of which shall reduce the time required to bring the drive up to normal operating speed following a break in the web.

Another specific object of this invention is to provide a novel magnetic-amplifier control circuit having general utility but particularly useful in accelerating the motor of a calender dryer to normal operating speed following a break.

The calender dryer motor of web processing apparatus is controlled by a device such as a saturable reactor which responds to the relationship between the motor speed and the shaft of the input calender to synchronize the operation of the motor and the input calender. Typically, the reactor may control the field of a generator which supplies the motor. This control system is provided with current-limit means which limits the current supplied to the motor so as to prevent excessive overloading of the motor. The synchronization is effected in dependence upon a signal which is generally equal to a function of the difference between a potential dependent on the speed at which the web is being advanced into the calender drive and a potential dependent on the speed of the motor. The current limit is effected by comparing the current load of the motor with a set potential and impressing a current-limit control signal to reduce sharply the supply of power to the motor when the current loading exceeds a predetermined magnitude.

In accordance with this invention, the reference signal during threading is set at a magnitude higher than the magnitude during normal generative operation so as to condition the motor to reach operating speed at a high rate and at the same time the current limit is set to permit substantial overloading of the motor. Typically, the current limit may be set to permit the motor to operate at 200% of rated load. This setting of the reference signal and the current limit during threading conditions allows calender dryer drive to reach operating speed rapidly. It has been found in operation of apparatus in the practice of this invention that following a break in the web the calender dryer drive reaches operating speed in a time interval of the order of one minute. Thus nine minutes per day are saved in shut-down time following breaks. This saving amounts to $\frac{3}{4}$ of the \$180,000 per year lost in shut-down time or about \$135,000 per year for each calender dryer unit of the apparatus.

In the preferred practice of this invention, both the reference signal supply circuit and the current limit circuit are maintained permanently set for threading. The transition from the threading setting to the normal operating setting is effected by a relay which responds to a change in loading of the motor automatically to reset the apparatus for threading.

The novel features considered characteristic of this invention are disclosed generally above. A clearer understanding of this invention both as to its organization and as to its method of operation, together with addi-

tional objects and advantages thereof will be derived from the following detailed description taken in connection with the accompanying drawings, in which:

FIGURE 1 is a diagrammatic view showing a web processing system in which this invention is incorporated;

FIGS. 2A, 2B and 2C together constitute a schematic of a preferred embodiment of this invention;

FIGS. 3A, 3B and 3C together constitute a schematic similar to FIGS. 2A, 2B, 2C, but showing the magnitudes and the types of the components of apparatus in accordance with this invention which was constructed and found to operate satisfactorily; and

FIGS. 3A and 3B are included herein only for the purpose of aiding those skilled in the art in practicing this invention and not with any intention of in any respect limiting the scope thereof.

The magnitudes of the resistances of the various adjustable or variable resistors in FIGS. 3A, 3B, 3C are represented as a number followed by a slant line followed by a larger number. The number to the left of the slant line indicates the setting of the corresponding resistor. Thus in actual practice, resistor 14R is set at 3000 ohms, resistor 15R1 at 2800 ohms, resistor 15R2 at 3750 ohms and resistor 7R at 40 ohms (FIG. 3C).

FIGURE 1 shows the portion of a web processing system in which this invention is incorporated. The overall apparatus may include a number of such systems. The apparatus shown in FIG. 1 includes an input or first calender C1, an output or second calender C3 and a calender dryer DC interposed between the calenders C1 and C2. The calender C1 includes a plurality of rolls r1 and Dr1 through which the web W is passed. Certain of the rolls are driven by a drive (not shown). The line shaft LS connected by drive roll Dr1 which advances the web W from the calender C1 is coupled through an alternating-current pilot generator PG1. PG1 produces an alternating current dependent on the speed of this shaft LS. The amplitude of this alternating current is proportional to the speed of roll Dr1 and this in turn is proportional to the speed of the web. The alternating current produced by PG1 is used in synchronizing the movement of the web as it leaves calender C1 with its movement to the other portions of the apparatus.

The output calender C3 also includes a plurality of rolls r3 and Dr3 over which the web is advanced after it leaves the calender dryer DC. The calender C3 may transmit the web W to additional processing apparatus and may be synchronized with the latter.

The calender dryer DC includes a plurality of rolls r2 which are driven from a direct-current motor M1. The motor is energized from a generator G which in turn is driven by a three-phase motor MD energized from the supply. (See FIGS. 2A-2B.) The motor M1 also drives an alternating-current pilot generator PG2 which produces an alternating potential, the amplitude of which is dependent, preferably proportional to, the speed of the motor M1. PG2 cooperates with PG1 to provide a reference signal maintained for proper synchronism of the drives for web W.

The drives for calenders C1 and C3 are of very high power. The drive for the dryer calender DC is of relatively low power of the order of $\frac{1}{10}$ of either of the drives C1 or C3. In the usual practice of this invention the calender C3 may be driven at a somewhat higher speed than the calender C1 and the web between C3 and DC is under tension. Under such circumstances the web in the calender dryer DC drives the motor M1 and the latter operates regeneratively supplying power to the generator G rather than absorbing power from the generator.

In the event of a break in the web at a point X for example, the drive of the calender dryer DC would assume the full load of advancing the web W from calender C1 through the calender dryer DC. The power required to advance the web is high compared with the power rating of the drive G-M1. Typically, the drive G-M1

10
15

may have a rating of 40 horsepower and the demand on G-M1 to advance the web W from the calender C1 to the calender dryer DC without the aid of C3 may be controlled in dependence upon the relationship between the drive G-M1 the power supplied to the generator G is of the order of 350 horsepower. To prevent damage to the potentials from PG1 and PG2 so as to prevent the drive DC from attempting to operate at a high speed and in addition a current-limit control is introduced which prevents overloading of the generator G.

Specifically, the apparatus in accordance with this invention includes a DRIVE and a CONTROL (see FIGS. 2A, 2B, 2C). The division of the apparatus in this way is on a functional and not a structural basis. The DRIVE and the CONTROL may be subdivided into components in separate cabinets which may be disposed in different parts of the installation. For example, there may be parts at the operator's station, near calender C1, near calender C3 or near the calender dryer.

This apparatus is supplied from the conductors L1, L2, L3 which may be connected to the buses of a three-phase supply through the usual disconnects or circuit breakers (not shown). The controlling components of the DRIVE and the CONTROL are supplied from direct-current conductors P and N which may be energized from conductors L1 and L3 through contacts 1Ma and 1Mc through a transformer AT and a rectifier 1RX. The potential for the current-limit control is derived from conductors L1, L2, L3 through the contacts 1Ma, 1Mb, 1Mc of contactor 1M and rectifier 5RX which is energized by the secondary AS1 of the transformer AT1. Single-phase alternating current for control purposes is derived from conductors AL1 and AL2 energized from conductors L1 and L3 through contacts 1Ma and 1Mc through a constant-potential transformer KT which may, for example, be a SOLA transformer.

The DRIVE includes a main generator G, a motor M for driving the generator and the drive motor M1 which drives the rolls r2 of the calender dryer DC. The motor M is adapted to be supplied from the conductors L1, L2 and L3 through the contacts 1Ma, 1Mb, 1Mc of the contactor 1M. The coil of the contactor 1M is adapted to be connected between conductors L1 and L3 through a normally closed stop push-button SP and a normally open start push-button ST and to be locked in through its front contact 1Md.

The generator G has a commutating field winding FC, a series field winding FS, a shunt field winding GF and a differential shunt field winding GFD. The motor M1 has a commutating field winding FC1, a series field winding FS1 and a shunt field winding M1F. The generator G is adapted to be connected in power interchanged relationship with the motor M1 through the commutating winding FC, the series field winding FS, a low resistor 3R, the series field winding FS1, the commutating winding FC1 and a contact Ma of a contactor M in the CONTROL.

The generator G may operate generatively to supply motoring power to the motor M1 in situations where the motor M1 is being brought up to starting speed or to operating speed. The generator G and the motor M1 may also operate regeneratively in which case the motor M1 supplies power to the generator G.

In accordance with the specific aspects of this invention, provisions are included for producing a response to a change in the current flow either from the generator G to the motor M1 or from the motor M1 to the generator G on the occurrence of such an event as a break in the web. These provisions include relays AAV and DAV in the CONTROL. The relay DAV responds in situations in which the motor M1 is feeding power to the generator G, the relay AAV responds in situations in which the generator G is feeding power to the motor M1. The coil of relay DAV is adapted to be connected across the windings FC, FS and FS1 and the resistor 3R through

a rectifier 2RX and the front contact REV_a of the reverse relay REV which is actuated when the operation is regenerative from the motor M1 to the generator G. The coil of AAV is adapted to be connected similarly through the rectifier 3RX and the contact FW_{Da} when the operation is generative and the flow of power is from the generator G to the motor M1.

The control of current through the main shunt field winding GF of the generator G is controlled by magnetic amplifier MA. This amplifier has an output winding WO, a bias winding WB, an inching winding WI, a voltage control winding WV, damping windings WD and WD₁, current limit windings WCL, reference winding WR and speed winding WS. The field winding GF is supplied from conductors AL₁ and AL₂ through the winding WO and through the rectifier 4RX connected in the usual rectifying relationship with the winding WO.

There is a dot adjacent each winding to show the effect on the output through WO of ampere turns through the winding. Positive current flowing from the dot through the winding tends to increase the output through WO and positive current flowing through the winding to the dot tends to decrease the output through WO. Thus an increase in ampere turns through winding WR results in an increase in the ampere turns through WO and a decrease results in a decrease in the ampere turns through WO. The main shunt field GF of the generator G varies with the output of WO so that an increase in the output through WO produces an increase in the field and a decrease through WO produces a decrease in this main shunt field. Under the influence of GFD the potential of G would be opposite to that shown in FIG. 2A. An increase in this potential would result in an increase in the ampere turns through WV which would result in an increase in the ampere turns through WV, and an increase in the current through GF. This would tend to counteract the current through GFD and reduce the opposite potential.

The bias winding WB is supplied from conductors P and N through a filtering capacitor 1C. The capacitor is charged by the potential drop across a variable resistor 3RH which is connected in series with a resistor 7R between P and N. The charging circuit for the capacitor 1C includes a resistor 6R. The bias winding WB is connected across the capacitor through resistor 6R1. Inchling winding WI is similarly supplied from a filtering capacitor 2C across which it is connected through a resistor 8R1. The filtering capacitor is adapted to be charged from conductors P and N through a front contact INC_a of a relay INC in the CONTROL and a resistor 9R and a variable resistor 4RH. The charging circuit for the capacitor 2C includes the resistor 8R. The voltage compensation winding WV is connected across the armature of the generator G and the field windings FC and FS through a back contact of contactor M in the CONTROL, a variable resistor 11R, and a fixed resistor 12R. The voltage winding WV operates to assure that the generator voltage is zero when the equipment is not in operation and the generator G is deenergized. Even a small voltage on the generator G would produce a surge through the contactor Ma when this contactor is closed. The voltage winding WV is also adapted to be connected across the armature of generator G, the field winding FC and the field winding FS through the inching contactor INC_b and through a resistor 10RH. The function of the winding WV in this case is to counteract the effect of the differential winding GFD so that the inching may be precise.

The damping windings WD and WD₁ are supplied from a variable resistor 5RH connected across the armature of the generator G to field winding FC and the field winding FS, the windings WD and WD₁ are connected in series to the arm of the resistor 5RH through a fixed resistor 13R and a capacitor 3C. The resistor 13R and the capacitor 3C operate to differentiate the potential derived from 5RH.

The current-limit winding WCL is supplied from the rectifier 5RX and the circuit through which it is supplied incorporates important features of this invention in its specific aspects. This circuit includes the resistors 21R₁, 20RH, 21R, 1RH, 2RH, 22R, 22RH and 22R₁ connected in series across the rectifier 5RX. These resistors operate to set the blocking potential derived from the rectifier 5RX which determines the voltage for which load reducing current starts to flow through the current-limit winding WCL. The selected voltage provided by this bank of resistors is balanced against the voltage derived across resistor 3R which carries the current flowing between the generator G and the motor M1. One terminal of this resistor is connected to the junction J3 of the resistors 1RH and 2RH and the other terminal of this resistor 3R is connected through the resistor 6RH and the winding WCL to the junction J which, in turn, is connected to the bank of resistors through rectifiers 6RX and 7RX. The rectifiers 6RX and 7RX are oppositely poled, 6RX conducting under the potential across the resistor 3R is produced by generative operation when the generator G is feeding the motor M1 and the other 7RX conducting during regenerative operation when the motor M1 is feeding the generator G.

The resistors 22R, 22RH and 22R₁ are during standby and during the threading operation shunted by forward relay back contact FW_{D_b}. Similarly, the resistors 21R₁, 20RH and 21R are shunted by REV_b during threading or standby. During threading or standby, the resistors 1RH, and 2RH are then effective. The adjustable arm of 1RH is connected to J2 through back contact REV_d; the adjustable arm of 2RH is connected to J1 through back contact FW_{D_d}. During standby and threading, the arm of 2RH is electrically negative by a relatively high potential with respect to point J3 to which the resistor 3R is connected. Current is conducted through WCL only if the potential across 3R resulting from the supply of current from generator G to motor M1 is greater than this potential between 2RH and J3. This means that current limit is not applied until the current through 3R is substantial. For example, if the arm of 2RH is at minus 10 volts relative to J3, current only flows through WCL if the drop across 3R is more than 10 volts with t₁ electrically positive relative to t₂. The flow of the current through WCL would reduce the output of generator G. The same relationship exists with respect to the potential between the adjustable arm of 1RH and J3. In this case again the regenerative current through 3R from t₂ to t₁ must produce a drop higher than the drop between the arm of 1RH and J3 before the current-limit winding WCL conducts current. In this case, the current through WCL increases the output of G to reduce the regenerative effect.

The point J1 is also adapted to be connected to the arm of variable resistor 22RH through front contact FW_{D_e}.

The potential impressed from rectifier 5RX at J1 or J2 when contacts REV_e or FW_{D_e} respectively are closed and contacts REV_d or FW_{D_d} are open is substantially smaller than the potential impressed through 1RH or 2RH when REV_d and FW_{D_d} are closed and REV_e and FW_{D_e} are open. A smaller potential then across resistor 3R in either case permits current to flow through the current-limit winding WCL. Usually the resistors 1RH or 2RH are set so that the current limit winding WCL is supplied with current when the flow through resistor 3R corresponds to about 200% of rated loading of the motor M1. The resistors 20RH and 22RH are usually operated over the range from 30% rated loading of the motor M1 to 110% rated loading.

Windings WR and WS cooperate to maintain the first calender and the calender dryer drive in proper synchronism. Winding WR is supplied from the pilot generator PG1 through rectifier 7RX and winding WS is supplied from pilot generator PG2 through rectifier 8RX. The

potential delivered by PG2 corresponds to the actual speed of the motor M1 and the potential delivered by PG1 corresponds to the speed of the line shaft or the speed at which the input calender C1 is supplying the web W. The ampere turns through WR are counteracted on the ampere turns through WS.

The potential of rectifier 8RX is impressed across WS through a filter, a fixed resistor 18R and an adjustable resistor 7RH. The filter includes capacitors 4C and 5C which are connected to the positive terminal of 8RX through resistors 19R and 20R respectively. A rheostat 24RH serving for metering purposes is connected across 5C. The output of rectifier 7RX is similarly filtered by capacitors 6C and 7C and resistors 16R and 17R respectively. The capacitor 7C is shunted by a variable resistor 26RH which also serves for metering purposes.

The potential derivable from 7RX is connected to the winding WR through a circuit which constitutes an important feature of this invention in its specific aspects. This circuit includes the resistors 14R, 28RH, 15R1 and 15R2 which are connected in series. In standby or threading operation, resistors 14R and 28RH are effective, resistances 15R1 and 15R2 being shunted by contact FWD_h or REV_h. During generative operation resistor 15R1 is effective and during regenerative operation the resistor 15R2 is effective. The effects of these variable resistors in the different modes of operation can be understood by a consideration of FIGURE 3C in which the magnitudes of the various resistances are presented.

During threading, the ampere turns through WR are higher than in the regenerative setting during running, and lower than in the generative setting during running. The motor then has the highest speed in the regenerative setting during running, next highest in the threading setting and the lowest in the generative setting during running.

The CONTROL includes in addition to the contactors M, 1M, 1NC and the relays REV, FWD, DAV and AAV, the contactors 2M and 3M and the relays ACR and VR. The coil of contactor 2M is adapted to be connected between conductors P and N through back contact VR_a, a contact APX_a of a photoelectric relay (not shown) which closes if the ventilation is adequate, a start push-button ST1 which is normally open, a normally closed stop push-button SP1 and a front contact ACRa of the relay ACR. Contactor 2M is adapted to be locked in through its own front contact 2Ma. During inching the coil of the inching contactor INC is adapted to be connected between conductors P and N through contacts VR_a, APX_a, inch push-button IC, 2Mb, and ACR_b. This coil of contactor INC is adapted to be locked in through its contact INCc. The coil of contactor M is adapted to be connected between conductors P and N through front contact 2Mc and to be locked in through contacts VR_b, ACRe, and Mb, and alternatively through INCd. The coil of contactor 3M is adapted to be connected between conductors P and N through front contact 2Mc.

When the apparatus is to be set for regenerative operation the load limit reverse push-button RS is closed and the coil of relay REV is adapted to be connected between conductors P and N through front contact 3Ma, normally closed push button RT, push button RS and interlock contact FWD_f. The coil of REV is adapted to be locked in through DAV_a if the voltage impressed across DAV is of appropriate magnitude. When the apparatus is to operate generatively the load-limit forward push-button FD is closed and the coil of the relay FWD is connected between conductors P and N through contact 3Ma, normally closed push-button RT, push-button FD, interlock contact REV_f. This coil is locked in through contact AAV_a of relay AAV if the voltage across the generator and motor is appropriate. The coil of relay ACR is connected between conductors AL1 and AL2 and this relay is actuated if there is potential between AL1 and AL2. The coil of relay VR is connected

across the armature of motor M1 and the field windings FC1 and FS1 and this relay is actuated if the potential across the armature of the motor M1 is of appropriate magnitude; that is, if the speed of the motor is above a predetermined magnitude. Relay VR remains unactuated at inching speeds.

During standby, the conductors L1, L2 and L3 are energized by the closing of the disconnects or circuit breakers (not shown). Start button ST is then closed energizing contactor 1M and locking this contactor in through 1Md. 1Ma, 1Mb and 1Mc are then closed and transformers AT and Kt and AT1 are energized. Potential is then produced between P and N at the output of rectifier 1RX and between AL1 and AL2. Relay ACR is actuated closing contacts ACRa, ACR_b, ACRe. APX_a is also at this time closed if the ventilation is adequate. Since AL1 and AL2 are energized, the output windings WO of magnetic amplifier MA are energized. The ampere turns through these windings is determined by the biasing ampere turns through WB and the ampere turns through WV and contact Md. These ampere turns are so set that the differential field GFD is counteracted and the potential of generator G is substantially zero. There is no current through the winding WR during standby because the contactor 3M is open and there is no current through WS during standby because the motor M1 is deenergized at Ma and the generator PG2 produces no potential. The motor M1 being deenergized, relay VR is deenergized. Relays AAV and DAV are deenergized. Since P and N are energized the fields of PG1 and PG2 and the field GFD are energized.

Preliminary to the threading operation it may be desirable to inch the apparatus for various purposes. To accomplish this object the inch-button IC is closed, this picks up the inch relay INC and it is locked in across VR_a and APX_a through the inch contact INCc. INCd closes picking up contactor M, this connects generator G to motor M1 through contact Ma. In addition, Md is opened and the contact 1NCb is closed to set the voltage winding WV for inching. INCa is also closed to supply pattern current through the winding WI permitting the motor to operate at inching speed. The effect of the pattern winding WI is to set the motor M1 at a low speed. The ampere turns through winding WV regulates the voltage of the generator G during the inching. The speed of the motor M1 is not adequate to pickup VR.

In the standby condition, the start button ST1 is open, contactor 2M is deenergized, contactor M is then deenergized, contactor 3M is deenergized, and relays REV and FWD are deenergized. The inching button IC is also open so that the inching contactor INC is deenergized. The contactor M being deenergized, contact Ma is open and the generator G and motor M1 are disconnected. Contact Md is closed so that there is current through winding WV. This current is of such polarity as to reduce the voltage of generator G to zero. The inch contacts INCa and INCb are both open so that there is no pattern ampere turns through the winding WI. The inch button IC is usually operated repeatedly until the desired inching operation is completed.

The apparatus is now ready for threading and is set with relays REV and FWD unactuated so that the back potential blocking the current flow through winding WCL is high. The motor M1 is then conditioned to draw substantial overload current. In addition, the circuit which supplies current through WR is set for threading and the resistor 28RH is set for the desired threading speed. This resistor remains in this position throughout the operation of the apparatus.

It may now be assumed that the apparatus is to be set in operation that the first calender C1 is in operation feeding web W towards the calender dryer DC. The second calender C2 may also be assumed to be in operation. Since the first calender C1 is in operation the generator PG1 is supplying potential dependent on the

speed at which the web W is being fed towards the calender dryer but no ampere turns flow through WR since at this point contact 3Mb is open. The motor M1 is at this point also deenergized and no potential is supplied by PG2.

To carry out the threading operation, the start push-button ST1 is closed; this energizes contactor 2M which is locked in by its contact 2Ma. Contact 2Mc is closed energizing contactor M, contact 2Md is closed energizing contactor 3M. Contactor 3Ma is closed conditioning the load limit reverse and load limit forward circuits to be actuated.

The actuation of contactor M closes contact Ma connecting the generator G and the motor M1 in power interchange relationship. Md is opened deenergizing the voltage winding WV. 3Mb closes energizing WR from the generator PG1. At this point, the reference circuit is set with the resistances 14R and 28RH controlling the current through the reference winding. Excitation of the generator is now increased and the potential supplied by the generator G to the motor M1 increases bringing the motor M1 up to speed. The reference ampere turns through WR is balanced against the speed ampere turns through WS produced by the pilot generator PG2 so that the generator voltage is essentially proportional to the net signal derived from the reference and speed windings. The operator may adjust the rheostat 28RH to vary the reference signal so as to match the speed of the motor M1 with the speed at which the web is being supplied. Once the proper threading speed is attained the precise speed match of the motor M1 and the calender C1 is achieved and the rheostat 28RH may remain set so that on the return to any threading operation following a break the precise threading speed is achieved. With the relays FWD and REV deenergized the current limit circuit is set to permit substantial overload during the threading operation. The threading operation may be interrupted if necessary by opening the stop button SP1.

When the motor M1 reaches substantial speed the relay VR is actuated locking in the contactor M through VRb, ACRe, Mb. The push-button ST1 is released once the desired speed is achieved and if the motor voltage drops for any reason the contact VRb opens deenergizing the contactor M and opening the motor supply circuit.

Once the web W is threaded through the apparatus it is necessary to set the apparatus into normal running operation. The apparatus may be set in two ways. The web between the calender dryer DC and the calender C3 may be tensioned and the web between the calender C1 and the calender dryer DC may be in a loop or the web between the calender dryer DC and the calender C3 may be in a loop and the web between the calender C1 and the calender dryer DC may be tensioned. The first mode of operation is achieved by setting the apparatus to operate regeneratively, that is with the motor M1 supplying the generator G. This object is accomplished by closing the reverse push-button RS. Relay REV is then actuated closing contact REVa and connecting the coil of relay DAV between the motor M1 and the generator G. In addition, REVh opens connecting resistor 15R2 in circuit with WR and REVg closes short circuiting resistors 4R and 28RH. WR is now supplied with lower current than during threading since 15R2 is greater than 4R and 28RH (see FIGS. 3A and 3B). The power output of the generator is then decreased and since the counter electromotive force of the motor M1 is not changed the motor regenerates. The regenerative current causes relay DAV to be energized through rectifier 2RX, this locks in relay REV and the push-button RS may be released. In addition, the actuation of REV closes contact REVe and opens contact REVd setting the current limit for substantially lower loading than it is set during threading. The current limit may be adjusted by setting the rheostat 20RH. If it is desired that the web be in a loop between C3 and DC and tight between C1 and DC

the apparatus is set for generative operation by closing push-button FWD. This actuates relay AAV across the generator G and the motor M1 and also setting the reference circuit with 15R1 controlling the ampere turns through WR. 15R1 is smaller than 4R and 28RH (see FIG. 3C) permitting larger current to flow through WR and increasing the potential of the generator G so that it feeds the motor M1. The speed of the motor M1 then increases slightly applying tension to the web between calender C1 and the calender dryer DC and producing a slight loop in the web between the dryer DC and the calender C3. In this case, the forward portion of the current limit circuit is set for controlling the current limit by the opening of contact FWDd and the closing of contact FWDc. Relay AAV is in this case actuated locking in the relay FWD so long as the current flowing through the field windings FC, FS and FS1 remains adequate.

The opening of load limit reset button RT deenergizes the relays REV and FWD and reverts the apparatus to the threading setting.

On the occurrence of a break in the web the speed of motor M1 decreases substantially causing either DAV or AAV, as the case may be, to drop out. This deenergizes the relay REV or FWD as the case may be and sets the apparatus for threading so that the reference ampere turns through WR is now controlled by resistors 4R and 28RH and the current limit by either resistor 1RH or resistor 2RH depending on the character of the operation. At the new setting the apparatus is set precisely for threading since the resistor 28RH is in the setting where it was left after the initial threading operation. The current-limit circuit is now set to permit substantial overload so that the generator G is driven in such a way that the motor M1 reaches the threading speed in a very short time of the order of a minute and the apparatus may be quickly reset for continued operation.

While a preferred embodiment of this invention has been disclosed herein, many modifications thereof are feasible. This invention then is not to be restricted except insofar as is necessitated by the spirit of the prior art.

The claims are:

1. Control apparatus including a motor, a generator, means connected to said generator for connecting said motor and generator in power-interchange relationship, means connected to said motor for deriving from said motor a potential dependent on the speed of said motor, means connected to said generator for deriving a potential dependent on the loading of said generator by said motor, magnetic amplifier means including output winding means, current-limit winding means, and reference winding means, the ampere turns through said reference winding means controlling the ampere turns through said output winding means, and ampere turns through said current-limit winding means varying the ampere turns through said output winding means so as to reduce the loading of said motor on said generator, current supply means for supplying a reference potential having alternatively a first magnitude for producing generative operation of said motor and generator, a second magnitude for producing regenerative operation of said motor and generator and a third magnitude intermediate said first and second magnitudes for accelerating said motor, means connecting said reference potential and said speed responsive potential in balancing relationship to said reference winding means, additional current supply means for supplying a blocking potential having alternatively a first magnitude corresponding to generative operation of said motor and generator, a second magnitude corresponding to regenerative operation of said motor and generator, and a third potential having an absolute magnitude substantially higher than said last-named first and second magnitudes corresponding to operation of said motor and generator in accelerating said motor, and means connecting said loading dependent potential in overriding relation to the current limit circuit of the apparatus.

tionship with said blocking potential to said current-limit winding means.

2. A drive for web treating apparatus including a calender dryer and means coupled to said web for advancing said web to said dryer, said drive comprising a motor, a generator, means connected to said generator for connecting said motor and generator in power-interchange relationship, means connected to said motor for deriving from said motor a potential dependent on the speed of said motor, means connected to said generator for deriving a potential dependent on the loading of said generator by said motor, magnetic amplifier means including output winding means, current-limit winding means, and speed comparing winding means, the ampere turns through said speed comparing winding means controlling the ampere turns through said output winding means, and ampere turns through said current-limit winding means varying the ampere turns through said output winding means so as to reduce the loading of said motor on said generator, means responsive to said web advancing means for supplying a reference potential having alternatively a first magnitude for producing generative operation of said motor and generator, a second magnitude for producing regenerative operation of said motor and generator and a third magnitude intermediate said first and second magnitudes for accelerating said motor, means connecting said reference potential and said motor
